UNITED STATES PATENT OFFICE.

WILLIAM M. VENABLE, OF PITTSBURGH, PENNSYLVANIA, ASSIGNOR TO BLAW STEEL CONSTRUCTION COMPANY, OF PITTSBURGH, PENNSYLVANIA, A CORPORATION OF NEW JERSEY.

WALL-MOLD.

1,103,109.

Specification of Letters Patent. Patented July 14, 1914.

Application filed October 9, 1912. Serial No. 724,726.

To all whom it may concern:

Be it known that I, WILLIAM MAYO VENABLE, a citizen of the United States, residing at Pittsburgh, in the county of Allegheny and State of Pennsylvania, have invented certain new and useful Improvements in Wall-Molds, of which the following is a specification.

The invention relates to molds or forms for use in the construction of concrete houses, and particularly for use in the construction of the walls of houses. It has for its primary objects, the provision of improved means for the construction of walls of varying thickness and length from the same parts, whereby the number of different parts required is reduced to a minimum; the provision of a construction in which the amount of labor incident to assembling and disassembling is reduced; the provision of a construction in which the adjustment of the length of the walls can be carried to a high degree of refinement without unduly increasing the number of parts of varying dimensions; and the provision of an apparatus which can be cheaply constructed, which can be operated by unskilled labor without danger of mistakes and which is exceedingly strong and rigid when in position for use. Certain embodiments of the invention are illustrated in the accompanying drawings, wherein—

Figure 1 is an assembly plan view showing the application of my invention to the construction of walls, Fig. 2 is a section on the line II—II of Fig. 1, Figs. 3 and 4 are enlarged detail views of one of the liner bars and the splice plate used in connection therewith, Fig. 3 being a plan view of the parts specified and Fig. 4 being a side elevation thereof, Fig. 5 is an enlarged detail sectional view through one of the spacer bars employed and its guard, Fig. 6 is an enlargement of the right hand end of the section shown in Fig. 2, Fig. 7 is a face view of one side of the portion of the form shown in section in Fig. 6, and Figs. 8 and 9 are plan and side elevation views respectively of the splice connection between the liner bars at one of the inside corners of the mold.

The elements or units from which the form or mold is built up consist of the usual rectangular plates provided at their edges with the outturned flanges. These units or

panels are made preferably in a limited number of standard sizes, and are secured together at the flanges by means of releasable connecting means extending preferably through perforations in the said flanges. 60 In order to secure slight variations in the dimensions of the walls to be built, such as cannot be secured by the use of the standard plates of varying size, filler plates are employed which overlap the standard panels 65 to a greater or less degree, depending upon the condition to be met, and the two sections of the wall joined by the filler plate are rigidly secured in fixed relative position by what may be termed liner bars. These liner 70 bars are secured rigidly to each section of the wall with their ends adjacent, and these ends are secured together by means of splice members which are secured detachably and adjustably to each of the liner bars. This 75 arrangement provides for the securing together of two adjacent sections of the wall in any desired relation, the connection occurring either between sections of the wall or mold which are in alinement, or between 80 sections which are at an angle. The filler plates employed may be located either between two sections of wall in alinement, or between two sections of wall or mold, at an angle to each other, and may be at an inside 85 corner, or at an outside corner, as will more clearly appear from a fuller consideration of Fig. 1 of the drawings later. The inner and outer walls of the mold are held securely in their proper relative position with 90 respect to each other by means of what may be termed space or tie bars, and such tie bars, in the preferred form of construction, also serve as means for securing the liner 95 bars rigidly in position. As will appear 95 more fully later, the liner bars may be placed upon one side only of the mold, or may be placed upon both sides, depending upon the conditions encountered, and may be placed either horizontally or vertically, 100 or both. Figure 1 of the drawing is designed to illustrate a variety of arrangements of the liner bars, filler plates and splice plates, such figure illustrating the application of the elements of my apparatus in 105 a variety of locations and conditions.

Referring first to that portion of the mold at the left hand end of Fig. 1, and shown in enlarged detail in Figs. 6 and 7, it will be seen that the opposing sides of the mold or 110

- form are built up of the panels 1-1 and 2-2 provided at their edges with angles secured to the plates constituting the bodies of the panels and having outturned flanges. 5 The flanges of adjacent panels abut each other as indicated in Figs. 6 and 7, and are perforated to receive slotted keys 3, whose slotted portions are engaged by the wedge shaped members 4 (Fig. 7). Adjacent panels 10 are thus detachably clamped together, and a wall of any desired extent may be secured, depending upon the number of panels employed. A convenient size for the panels is 24 inches by 24 inches over-all dimensions, 15 and in order to provide for varying lengths of walls I have found it desirable to use in connection with such square 24-inch panels other panels 24 inches long but only 12 inches and six inches in width, these three 20 sizes in connection with the adjusting means involving the filler plates and splice members to be hereinafter described, serving to construct walls varying in length by a quarter of an inch. 25 The two opposing walls or sides of the mold are held rigidly in their proper relative position by means of the space bars 5 whose construction will be very readily understood by reference to Figs. 6 and 7 in 30 connection with Fig. 1. These space bars 5 which are also sometimes known as tie bars, are tapered in order to permit of their more ready withdrawal from the concrete after it has set, and are each provided in their 35 ends with the plurality of slots 6 serving to provide for an adjustment in spacing between the two opposing walls. These space bars extend from one side of the mold to the other and pass between the panels 1 and 40 2 at their juncture, the opposing flanges of the panels being recessed to permit the passage of the space bars as indicated at 7 in Figs. 2 and 7. Keys 3 like the keys 3 here- 45 tofore described extend through the slots 6 at the outer ends of the bars 5 (see Figs. 1, 6, and 7) and through the abutting angles carried by the panels, such keys being secured by wedges 4. As indicated in Fig. 6, the bottom bar 5 and the third bar 5 from the bottom are secured at their ends only by 50 keys 3 as just described, but the other two bars 5 (as indicated in Fig. 6) are in addition secured to the liner bars which will now be described. 55 Extending transversely across the plates 2-2 constituting the inner wall of the form are the liner bars 9-9, such liner bars being in the form of commercial angles, and being constructed as indicated in the detail views 60 (Figs. 3 and 4). The vertical angles of these bars 9-9 are provided with the slots 10 for the passage of the ends of the space bars 5, and the ends of the horizontal flanges of the angles are provided with the plurality of closely spaced adjusting slots 11

used as hereinafter described, for securing the liner bar to a splice plate. It will be seen by reference to Fig. 7 that the space bars which come opposite the liner bars 9-9 pass through the slots 10 in such liner bars and are rigidly clamped to such liner bars by means of wedges 4, such wedges being similar to the other wedges 4 employed. It will also be seen that these liner bars 9-9 serve to bring into alignment the 70 plurality of plates 2-2 across which they extend, and that the outer wall composed of the panels 1 is also lined up by reason of the connection between the liner bars and the outer wall through the space bars. Further in addition to lining up the two walls the liner bars serve as stiffeners for such walls. If desired, these liner bars may be used on the outside wall as well as on the inside wall, such arrangement being shown in the upper wall illustrated in Fig. 1 wherein the inner wall is provided with the liner bars 9' and the outer wall is provided with the liner bars 9², the space bars 5 in such case passing through the vertical flanges of both the liner bars 9' and 9². 80

The liner bars also perform another function, which is to provide a connection between adjacent sections of the wall where a filler plate is interposed between such sections of the wall, in order to secure any desired adjustment as to the length of the wall. Where connection between adjacent wall sections occurs at the corner the splice plate is preferably triangular as indicated 95 in the plate 13 shown in Fig. 1 and in detail in Figs. 8 and 9. The two adjacent wall sections at this point are joined by means of the lap filler plate 14, so that the relation between the walls may be adjusted to 100 any desired degree of fineness by varying the lap between the filler plate 14 and the adjacent walls. The filler plate 14 is not secured to the adjacent panels but is held in position by the concrete. Before the concrete is applied the plate may be temporarily held against movement by any desired temporary holding means such as braces to the opposite wall or may be held by the workman until sufficient concrete is 110 supplied behind the plate to prevent its accidental movement. The spacing of the adjusting slots 11 (Fig. 3) at the ends of the liner bars is made slightly greater than the spacing of the slots 14' in the splice plate 120 13, so that a vernier adjustment may be secured between the liner bars and splice plates. For instance if the spacing of the slots 11 is made one inch and the spacing of the slots 14' is made three quarters of an 125 inch, the splice plate when placed on the liner bar will have holes which correspond with those in the liner bar every three inches, and another alignment of securing holes may be secured by slipping the mem- 130

bers on each other a quarter of an inch, so that a very fine adjustment may be secured without an unduly close spacing of the slots in the two members. As indicated in Figs. 5 and 9, the splice plate 13 is secured to the liner bars 9 and 9² by means of slotted keys 3 held by wedges 4 corresponding in all respects to the members 3 and 4 heretofore described. In order that the ends of the panels adjacent the splice plate 13 may be held against movement, the relatively short slotted tie bars 15 (Fig. 8) are keyed to the angles of the panels by means of the keys 3 and wedges 4, and extend through the end slots 10 in the liner bars 9 and 9², and are held by wedges 4 similar to those heretofore described as holding the ends of the space bars to the liner bars. The tie bars 15 may be used in any case where it is desirable or necessary to dispense with the space bars 5, the liner bars being in that case held in position to the one wall by the short tie bars. It will be seen therefore that the two wall sections approaching at the corner may be rigidly and adjustably secured together by means of the splice plate attached to the liner bars, and that any desired adjustment is possible by reason of the filler plates 14 which overlap the two wall sections to a greater or less degree.

In some cases it may be desirable to employ filler plates in the straight portion of the mold instead of at the corner as heretofore described, and in such case the system of joinder remains substantially the same. The numeral 16 as applied to the left hand wall in Figs. 1 and 2 indicates filler plates supplied in the straight portion of the wall. In that case the liner bars 9 and 9² are in alinement, and a rectangular splice 17 is employed for securing the liner bars 9 and 9² together, such plate overlapping the ends of the two liner bars. This splice plate 17 is provided with the series of perforations corresponding to the perforations in the splice plate 13, so that a vernier adjustment between the two liner bars is secured, and the filler plates 16 may be made to overlap the wall sections a distance sufficient to secure the desired length of wall. In this construction the adjacent ends of the panels 2-2 are provided with the short tie bars 15-15 similar to those of Figs. 8 and 9, such bars being keyed to the flanges of the panels 2-2 and extending through the end slots 10-10 in the liner bars 9 and 9² (Fig. 7). The opposite side of the wall is provided with liner bars 9⁴ (Figs. 1 and 6) through which the space bars 5-5 extend and to which such bars are secured by the wedges 4-4. The adjacent ends of the panels 1-1 on opposite sides of the outer filler plate are secured to the bar 9⁴ by means of the short tie bars 15-15 (Fig. 1) as here-

tofore described for holding the edges of the plates 2-2 to the bars 9 and 9².

In the upper right hand corner of Fig. 1 is illustrated the application of the splice plate to the connection of exterior liner bars, such splice plate being indicated by the reference numeral 18 and serving to connect the liner bars 9² and 9³, the connection between the splice plate and the liner bars being substantially the same as heretofore described with respect to the splice plate 13. An outside corner filler plate 19 is employed in this case to fill the gap between the two walls approaching each other at an angle. Fig. 1 illustrates the application of the connecting means heretofore described, in a number of different conditions, whose application will be readily understood from the drawing, without further description.

In order to prevent the concrete from filling the slots 6 in the space bars (Fig. 6) when such slots lie between the side walls, and so prevent the ready withdrawal of the bars after the concrete has set, the U-shaped guard member 20 indicated in Figs. 5 and 6 is preferably employed. This guard member 20 extends substantially from one side wall to the other and incloses the space bar 5 in such manner as to prevent the access of the concrete to the perforations through the bar, so that after the concrete has set the bar is free to slide through the guard, such guard being left permanently embedded in the concrete.

Having thus described my invention and illustrated its use, what I claim as new and desire to secure by Letters Patent is the following.

1. In a mold, a side wall comprising a series of metal panels having their side edges provided with abutting flanges, means for detachably securing the flanges together, an opposing side wall, space bars secured to said opposing side wall and extending between the said abutting flanges and out of such flanges, a perforated liner bar extending across the faces of the said series of metal plates and resting against the edges of the said abutting flanges with the ends of the space bars extending through the said perforations in the liner bar, and releasable clamping means for securing the outwardly projecting ends of the said space bars to the liner bar.

2. In a mold, a side wall in two sections with the ends of such sections adjacent and each comprising a series of metal panels having their side edges provided with abutting flanges, means for detachably securing the abutting flanges together, a lap filler plate between the two sections of the side wall, a liner bar for each section extending across the faces of the panels of its section of the side wall, an opposing side wall spaced

- away from the first side wall, space bars secured detachably to said opposing side wall and extending between the said abutting flanges and to the liner bars, means for detachably securing the space bars to the liner bars, and an adjustable connection between the opposing ends of the liner bars carried by the two sections whereby such bars and the two sections of the side wall 10 are secured together.
3. In a mold, a side wall section consisting of a plurality of panels secured together at their edges, a second side wall section consisting of a plurality of panels secured together at their edges with the end of such section adjacent the end of the first section, a lap filler plate between the two side wall sections, a liner bar for each section extending across the faces of the panels of its section and rigidly secured against such panels to hold them in alinement, and an adjustable connection between the adjacent ends of the liner bars.
4. In a mold, a side wall section consisting of a plurality of panels secured together at their edges, a second side wall section consisting of a plurality of panels secured together at their edges with the end of such section adjacent the end of the first section, a lap filler plate between the two side wall sections, a liner bar for each section extending across the faces of the panels of its section and rigidly secured against such panels to hold them in alinement, a splice plate 35 overlapping the adjacent ends of the liner bars, a vernier arrangement of perforations being provided in the plates and bars, and securing means extending through registering perforations in the liner bars and splice 40 plates.
5. In a mold comprising a pair of opposing side walls each consisting of a plurality

of metal plates, of a space bar extending between the two walls and provided with a plurality of perforations to receive fastening means for securing connection to the walls so as to prevent inward or outward movement of either wall independent of the other, insertable fastening means for said perforations, and a sheet metal guard open at one side and adapted to be slipped over the space bar after it is secured to the two walls, and fitting the sides of such space bar so as to prevent access of concrete to the perforations.

6. In a mold, a side wall comprising a series of metal plates having their side edges provided with perforated abutting flanges, means for detachably securing the flanges together, an opposing side wall, space bars secured to said opposing side wall and extending between the said abutting flanges and out past such flanges, a liner bar extending across the face of said series of metal plates and resting against the said abutting flanges, the said spacer bars being provided with perforations spaced apart at definite intervals to provide adjustment between the side walls and adapted to receive securing means, securing means adapted to extend through the perforated flanges and through the perforations in the space bars, and other securing means adapted to pass through other of the said perforations in the space bars and clamp the space bars to the liner bars and the latter against the flanges.

In testimony whereof I have hereunto signed my name in the presence of the two subscribed witnesses.

WILLIAM M. VENABLE.
